United States Patent Office

Des. 191,276
Patented Sept. 5, 1961

191,276

WHEEL BLOCK

Walter F. Jicha and Marion C. Wilson, Hammond, Ind.,
assignors to Calumet Steel Castings Corporation,
Hammond, Ind., a corporation of Indiana

Filed Apr. 11, 1960, Ser. No. 60,129

Term of patent 14 years

(Cl. D41—1)

Fig. 1.

Fig. 2.

Fig. 4.

Fig. 3.

FIG. 1 is a rear perspective view of the wheel block of the present design;

FIG. 2 is a front perspective view thereof;

FIGURE 3 is a vertical sectional view of the wheel block taken on a plane passing through the center thereof; and

FIGURE 4 is a sectional view thereof taken on the line 4-4 of FIGURE 3.

We claim:

The ornamental design for a wheel block, substantially as shown.
